(57) **CLAIM**

The ornamental design for a path light as shown and described.

DESCRIPTION

FIG. 1 is a perspective view of the first embodiment of a path light showing my new design;

FIG. 2 is another perspective view thereof;

FIG. 3 is a front view thereof;

FIG. 4 is a back, left and right view thereof;

FIG. 5 is a top view thereof;

FIG. 6 is a bottom view thereof;

FIG. 7 is a perspective view of the second embodiment of the path light showing my new design;

FIG. 8 is another perspective view of the second embodiment of the path light of FIG. 7;

FIG. 9 is a front view of the second embodiment of the path light of FIG. 7;

FIG. 10 is a back view of the second embodiment of the path light of FIG. 7;

FIG. 11 is a left view of the second embodiment of the path light of FIG. 7;

FIG. 12 is a right view of the second embodiment of the path light of FIG. 7;

FIG. 13 is a top view of the second embodiment of the path light of FIG. 7; and,

FIG. 14 is a bottom view of the second embodiment of the path light of FIG. 7.

The broken lines depict portions of the path light and form no part of the claimed design.

1 Claim, 14 Drawing Sheets
